ADJUSTABLE TENSION HINGELESS
VENTILATOR

Daniel Allcott Kelly, Salem, Va., assignor to Graham-
White Sales Corporation, Salem, Va., a corporation of
Virginia

Filed Feb. 4, 1966, Ser. No. 525,028
6 Claims. (Cl. 98—2)

This invention relates to hingeless ventilators and is an improvement on ventilators of the type disclosed in Kelly et al. Patent No. 3,102,464, issued on Sept. 3, 1963.

An object of the invention is to provide an improved hingeless ventilator which depends on tension to press a closure member against a seat and wherein the tension is adjustable for compensating initially for manufacturing tolerances and later for set or wear.

Another object of the invention is to provide an improved hingeless ventilator which depends for operability on a tensile force applied between its closure member and a guide bar and the closure member and guide bar are so connected as not only to enable the tensile force to be adjusted but to supply at least part of that force.

Other objects of the invention will appear hereinafter in the detailed description and be particularly pointed out in the appended claims and illustrated in the accompanying drawings, in which:

FIGURE 1 is an interior plan view of a preferred embodiment of the hingeless ventilator of the present invention;

FIGURE 2 is a vertical sectional view taken along lines 2—2 of FIGURE 1; and

FIGURE 3 is an enlarged vertical sectional view taken along lines 3—3 of FIGURE 1.

Referring now in detail to the drawings in which like reference characters designate like parts, the preferred embodiment of the improved hingeless ventilator of the present invention is similar to that of the Kelly et al. patent in having a closure member or cover 1 which is swingable to open and close an opening 2 in a wall 3 of a vehicle cab or other compartment (not shown) and is held in position against one side of the wall and guided in its movements by the sliding engagement of a guide or positioning bar or rod 4 with guide members 5 fixed to the wall's opposite side. The preferred ventilator includes a frame 6 bounding the opening 2 and riveted or otherwise fixed to the wall 3 about an aperture 7 therein.

Mounted on the outside of the frame 6, the closure member 1 is generally rectangular in cross-section and bounded by an inturned or instanding peripheral lip or flange 8 which in closed position surrounds or encircles and overlaps an outturned or outstanding flange 9 bounding the also generally rectangular opening 2. Identical or counterpart and longitudinally aligned, the guide members 5 are fixed to and instand or project inwardly from the frame 6 and each has an inwardly facing guideway 10 along which the guide bar 4 slides. Each guideway 10 is divided laterally into a pair of coradial or equal radius, cylindrically convex sections 11, each substantially concentric with and struck about the closure member's opposite swinging axis, which in the illustrated embodiment is substantially at the base of the frame flange 9 on the far side of the opening 2. At its center or midpoint between the side sections 11, each guideway 10 has a concave center seat 12 for seating the adjoining end of the guide bar 4 in the closed position of the closure member 1.

For transmitting the movements of the guide bar 4 along the guideways 10 to the closure member 1, the latter has fixed to its inner side or face 13, adjacent its opposite ends and inwardly of the frame flange 9, a pair of arms 14, instanding or projecting inwardly normal to

2

that face through the opening 2 and receiving the ends of the guide bar 4 inwardly of the guide members 5 in longitudinally elongated slots 15. Either the guide bar 4 or, as illustrated, a web 16 connecting the arms inwardly beyond the guide bar can be used as the handle for swinging the closure member between open and closed positions. A rubber or like resilient pad 17 lining or applied to the inner face 13 of the closure member 1 and engageable with the entire inner end of the frame flange 9, seals the opening 2 in the closed position of the closure member.

The ventilator is dependnet on tension exerted by a resilient or spring force between the closure member 1 and the guide members 5 for holding the closure member and the guide bar 4 respectively against the frame flange 9 and the guideways 10. The necessary tension or tensile force is obtained through a connector 18 connecting the guide bar 4 at substantially its longitudinal center or midpoint to the middle or center of the closure member 1. As opposed to the correspondingly positioned connecting means of the second embodiment of the Kelly et al. patent, the connector or connecting means 18 of the ventilator of this application is longitudinally adjustable or variable in its effective length to enable the tensile force to be adjusted both in the course of and after the initial installation of the ventilator. There will be variations between ventilators due to manufacturing tolerances and, when made of materials now available, the resilient sealing pad 17 will take a permanent set after a time in the areas in which it contacts the seat for the closure member 1 on the frame flange 9. These factors, as well as wear in use, cannot be compensated for or accommodated with a fixed-length connecting means, such as shown in the patent. By contrast, the adjustable connector 18 of this invention not only makes it possible to maintain the tensile force uniform throughout the ventilator's effective life but also facilitates assembly and disassembly of the closure member 1 and the frame 6.

With the side sections 11 of the guideways 10 of the same radius and each struck about the opposite or related swinging axis of the closure member 1, whatever the source, the tensile force available for holding the closure member 1 in any partly or fully open position, is the same over the range of movement of the guide bar 4 along the side sections 11. As indicated by the configuration and disposition of the central seat 12 in which the ends of the guide bar 4 seat in the closed position of the closure member 1, a somewhat lesser tensile force suffices to hold the closure member in that position. If the guide bar 4 is a spring bar and the tensile force is derived entirely from the flexing of that bar, the connector 18 need only be adjustable in length to enable the force to be adjusted initially and thereafter maintained. However, if the connector is both longitudinally adjustable and resilient, the same connector can be used whether the guide bar 4 is rigid or flexible, the resilience in the connector then either supplying the whole resilient force or supplementing the force derived from the flexing of the guide bar.

Preferred for its adaptability for use with either a rigid or a flexible guide bar 4, the illustrated connector 18 is both resilient or longitudinally yieldable and longitudinally adjustable. The preferred connector includes a hook bolt 19 having a hook 20 at its inner end for slidably receiving and gripping the preferably annularly grooved middle or midpoint of the guide bar 4 and a stem 21 projecting outwardly from the hook through an apertured web or flange 22 in a bracket 23 fixed or anchored to the inner face 13 of the closure member 1. As preferred, the bracket 23 may be the illustrated U-shaped yoke or of other suitable shape with the apertured web or flange 22 conveniently disposed parallel to and spaced inwardly from the inner face 13. A coil spring

24 around the stem and acting between the web 22 and a nut 25 threaded onto the outer end of the stem, yieldably resists elongation of the connector 18 formed by the bolt 19 and bracket 23, while turning of the nut on the stem permits the effective length of the connector and thus the tensile force exerted between the closure member and the guide members 5 to be varied as desired and at any time.

Extending or disposed substantially normal to the inner face 13 of the closure member 1, the connector 18 not only permits adjustment of the tensile force between the guide bars and the closure member, but the releasable engagement of the hook 20 with the guide bar 4 facilitates the otherwise difficult task of applying and removing the guide bar in process of assembling and disassembling the ventilator.

From the above detailed description it will be apparent that there has been provided an improved hingeless ventilator which, while dependent for operability upon a tensile force, enables that force to be adjusted as necessary at any time. It should be understood that the described and disclosed embodiment is merely exemplary of the invention and that all modifications are intended to be included that do not depart from the spirit of the invention and the scope of the appended claims.

Having described my invention, I claim:

1. A hingeless ventilator for ventilating a compartment through an opening in a wall thereof, comprising a closure member swingable against an outer side of said wall for opening and closing said opening, spaced guide members fixed to and standing from an inner side of said wall, inwardly facing guideways on said guide members, a guide bar spanning said opening and slideable on said guideways, arm means fixed to said closure member and connected to said guide bar for causing said closure member to swing on said wall in correspondence with movements of said guide bar along

5

4
said guideways, and means releasably connecting said guide bar and closure member for enabling a tensile force to be applied urging said guide bar into engagement with said guideways and said closure member into engagement with said wall, said connecting means being adjustable in length for varying said force.

2. A ventilator according to claim 1 wherein the guide bar is a spring bar, the arm means are spaced and the connecting means is positioned therebetween, and at least part of the tensile force is derived from flexing of the guide bar.

10 3. A ventilator according to claim 1 wherein the connecting means includes and is yieldably resisted in elongation by spring means, and at least part of the tensile force is derived from said spring means.

15 4. A ventilator according to claim 1 wherein the connecting means connects the guide bar and closure member substantially at their centers, and the connecting means includes a hook releasably engaging the guide bar and a bracket anchoring the hook to the closure member.

20 5. A ventilator according to claim 4 wherein the hook is an inner part of a hook bolt, the bracket is apertured to slidably receive a stem of the bolt, and the length of the connecting means is adjusted by a nut threaded onto the outer end of the bolt stem.

25 6. A claim according to claim 6 wherein a coil spring encircling the bolt stem and acting between the nut and the bracket yieldably resists elongation of the connecting means.

30

35

3. A claim according to claim 6 wherein a coil spring encircling the bolt stem and acting between the nut and the bracket yieldably resists elongation of the connecting means.
